US00D983020S

(12) **United States Design Patent** (10) Patent No.: **US D983,020 S**
(45) Date of Patent: **** Apr. 11, 2023**

(54) **FIXING BRACKET**

(71) Applicant: **GEROX WORKS, S.L.**, Rat Penat (ES)

(72) Inventor: **Carlos Joaquin Gusi Gracia**, Rat Penat (ES)

(**) Term: **15 Years**

(21) Appl. No.: **35/512,332**

(22) Filed: **Jun. 4, 2021**

(80) **Hague Agreement Data**

Int. Filing Date: **Jun. 4, 2021**

Int. Reg. No.: **DM/215543**

Int. Reg. Date: **Jun. 4, 2021**

Int. Reg. Pub. Date: **Aug. 6, 2021**

(30) **Foreign Application Priority Data**

Dec. 7, 2020 (EM) 008311179-0004

(51) **LOC (14) Cl.** **08-05**

(52) **U.S. Cl.**

USPC **D8/354**

(58) **Field of Classification Search**

USPC D8/354; D12/223

CPC F16B 2/20; F16B 2/185

See application file for complete search history.
